VIRGIL PRICE, OF NEW YORK, N. Y.

Design No. 4,264, dated July 26, 1870.

DESIGN FOR THE TIP OF A SWORD-SCABBARD.

The Schedule referred to in these Letters Patent and making part of the same.

To all whom it may concern:

Be it known that I, VIRGIL PRICE, of the city of New York, in the county and State of New York, have invented a new and original Design for the Tip of a Sword-Scabbard; and I do hereby declare that the following is a full, clear, and exact description thereof, which will enable others skilled in the art to make and use the same, reference being had to the accompanying drawing forming part of this specification.

The drawing represents a face view of my new design for tips of sword-scabbards.

This invention relates to a new design for the tip

of a sword-scabbard, and consists in the application thereto of three spears, *a a*, which cross each other in the manner indicated in the drawing.

A is the body of the scabbard, and
B, the tip, both being of suitable form.

I claim as my invention—

The design for the tip of a sword-scabbard, as shown.

VIRGIL PRICE.
